UNITED STATES PATENT OFFICE.

SAMUEL LAWSON, OF CROTON-ON-HUDSON, NEW YORK.

GAS-ENGINE.

1,367,320.

Specification of Letters Patent.

Patented Feb. 1, 1921.

Application filed April 9, 1917. Serial No. 160,724.

To all whom it may concern:

Be it known that I, SAMUEL LAWSON, a citizen of the United States, residing in Croton-on-Hudson, in the county of Westchester and State of New York, have invented an Improvement in Gas-Engines, of which the following is a specification.

This invention relates to internal combustion engines in the class designated as gas engines, and more particularly to the valves employed in this type of engine to admit the explosive mixture to the cylinders of the engine and to permit the exhaust gases to escape therefrom. The valve made in accordance with my present invention is a tubular valve and is so constructed and employed with the required ports in the head of the engine as to serve as a unitary structure for the admission and exhaust valve for a plurality of cylinders.

I am aware that heretofore various forms of cylindrical valves have been employed in gas engines. For example, disk valves have been used to admit the explosive mixture to engine cylinders and to permit the escape of the exhaust gases therefrom, such disk valves being placed in a valve casing secured on the head of the engine cylinders. These cylindrical valves have also been so constructed as to surround one end of the cylinder of the engine and to be inclosed in a valve casing adapted to contain the same, both these types of valve being actuated by suitable mechanism driven from the main shaft of the engine. In these instances however, as well as all others to which my attention has been directed it has been customary and so far as I am aware, been considered necessary to employ a separate valve for each individual cylinder. The main object therefore of this invention is to employ a unitary valve and a casing therefor so constructed, as hereinbefore stated, that the valve is adapted to admit an explosive mixture and to permit the escape of the exhaust gases from a plurality of cylinders, and the invention will be hereinafter more particularly described in connection with the accompanying drawings.

In the drawings,

Figure 1 is a plan and partial cross section of a gas engine made in accordance with my invention.

Fig. 2 is a cross section taken on line 2—2, Fig. 1.

Fig. 3 is a cross section taken on line 3—3, Fig. 2, and

Fig. 4 is a perspective view of the tubular valve.

In these drawings I have illustrated and will hereinafter describe my invention as applied to a two cylinder engine although as will be understood, the form of valve to which this invention relates may be equally well adapted for use in an engine having any desired number of cylinders.

In the drawings 10 indicates a bed plate upon which the engine rests and which is provided with a frame 11 extending upwardly therefrom to suitably support the engine cylinders 12 and 13 which will be understood are suitably secured in the frame. This however, may be done in any desired manner and forms no part of the present invention.

The cylinders 12 and 13 are provided with a cylinder head 14 which is preferably common to both the cylinders and is secured in position thereon by means of tie-bolts 15 which as indicated in the drawing and particularly in Figs. 2 and 3 pass through the chamber 16 for the circulation of a suitable cooling medium through the walls of the engine cylinder. As is usual each of these cylinders is provided with a piston, the one in the cylinder 12 being indicated at 17, and is provided with suitable packing rings 18 as is also customary. In this as well as in the other pistons employed, there is a pin 19 by which the piston is connected through a rod 20 to the drive shaft 21 of the engine.

The cylinder head and valve case 14 is also provided with suitable passages 22 and 23 for the circulation of a cooling medium and these passages may be connected to or independent of the passages 16 in the walls of the engine cylinder. The cylinder head 14 is also provided with suitable tapped openings 24 and 25 for the reception of suitable spark plugs for the cylinders 12 and 13 respectively. Centrally the cylinder head 14 also includes a valve case 26 inclosing a chamber for the reception and operation of the valve hereinafter described. Also in this cylinder head and making communication between the valve chamber and the respective cylinders, there are intake and exhaust passages. The intake passage to the cylinder 12 is indicated at 27 while the intake passage to the cylinder 13 is indicated

at 28. The exhaust passage from the cylinder 12 is indicated at 29, and the exhaust passage from the cylinder 13 is indicated at 30.

5 Within the valve casing 26 I employ a tubular valve indicated at 31. This valve centrally is provided with a transverse partition 32 dividing the same in this instance into an inlet chamber 33 and an exhaust chamber 34. In the walls of the valve embracing the inlet chamber there is an intake port 35, and in the walls of the valve embracing the exhaust chamber there is an exhaust port 36. Adjacent one end the valve 10 is provided with a flange 37 having a circular recess on its inner face adapted to receive the packing 38. This flange and packing in the use of the valve abut against the adjacent side of the head of the cylinder as 15 clearly indicated in Figs. 1 and 3. The opposite end of the valve is preferably of reduced diameter as indicated at 40 providing a shoulder 41 between the main portion of the valve and this reduced end thereof. 20 This end of the valve fits within an inlet nozzle 42 suitably secured to the cylinder head and having an inlet connection 43, with which an inlet port 43' in the valve is adapted to register during the revolution 25 of the valve within its casing.

This valve is geared to the main or drive shaft of the engine so as to turn once to every two revolutions of the drive shaft. As indicated in the drawing, the reduced end 30 of the valve is fitted with a spiral gear 44 which is secured in position thereon by a pin 45 or otherwise. This gear 44 meshes with a similar gear 46 secured on a shaft 47 by a key 48 or otherwise and on which shaft 35 there is also a gear meshing with a gear on an arbor 49'. The gear 49 meshes with a worm 50 secured on a shaft 51 which also carries a worm 52 meshing with a gear 53 on the main or drive shaft of the engine, it 40 being understood that while I have herein described the use of spiral gears for driving the valve, any other suitable mechanism 45 may be employed for this purpose, without departing from the nature and spirit of my 50 invention.

The engine hereinbefore described is a four cycle apparatus as is customarily used in engine practice at the present time; that is to say in each cylinder there is an admission stroke, a compression stroke, an explosion stroke, and an exhaust stroke. For the purposes of explaining the operation of the valve it will be assumed that the piston in the cylinder 12 is at the beginning of the 55 intake stroke and that the piston in the cylinder 13 is at the beginning of the exhaust stroke, and by reference to the drawing, it will be seen that the inlet port 35 is about to open to the passage 27 to admit the explosive mixture into the cylinder 12 and the

exhaust port 36 is about to open to the exhaust passage 30 in the cylinder 13. During these strokes of these pistons, these ports remain open, that is the port 35 opens the inlet chamber to the passage 37, and the port 36 opens the passage 30 to the exhaust chamber 34. During the next quarter revolution of the main shaft and during the intake stroke of the piston in the cylinder 13, the port 35 is open to the passage 28 leading to the cylinder 13. In this stroke also as will be understood, the compression takes place in the cylinder 12. During the next quarter revolution of the main shaft the explosion occurs in the cylinder 12 and the compression in the cylinder 13 during both of which as will be understood the intake and exhaust ports are closed. During the next quarter revolution of the main shaft the port 36 is open to the exhaust port in the cylinder 12, permitting the exhaust gases to escape therefrom, and as will be understood, this completes the cycle and the parts have returned to the position in which they were assumed to begin the cycle or that shown in the figures of the drawing. Furthermore, as will be understood, the intake port 43' is of such an extent that the passage of the intake through the nozzle 42 is open from any suitable source of supply, 95 during the entire period, when in the revolution of the tubular valve, the same is passing from the intake position to the cylinder 12 through the intake position to the cylinder 13. It will also be understood that a suitable exhaust pipe 39 may be connected to the tubular valve so as to convey the exhaust gases from the exhaust chamber therein.

I claim as my invention:

1. In a gas engine, a pair of cylinders, a valve casing, a tubular rotating valve having an intake chamber and an exhaust chamber therein, there being a single intake port in the walls of the valve inclosing the intake chamber for supplying both said cylinders, a single exhaust port in the walls of the valve inclosing the exhaust chamber for exhausting both said cylinders, and a port in the walls of the valve inclosing the intake chamber for the admission of an explosive mixture to the said intake chamber which latter named port is open to a supply passage in said valve casing during the time the said intake port is opened to both the said cylinders and closed at other times during the revolution of the valve.

2. In a gas engine, a pair of cylinders, a valve casing, a tubular rotating valve closed at one end and provided approximately centrally with a transverse partition wall dividing the same into an intake chamber and an exhaust chamber, there being a single intake port in the walls of the valve inclosing the intake chamber for supplying both said cyl-

- inders, a single exhaust port in the walls of the valve inclosing the exhaust chamber for discharging both said cylinders, and a port adjacent the closed end of the valve for the 5 admission of an explosive mixture to the said intake chamber, which last named port is open to a supply passage in said valve casing from the time the said intake port is opened to one cylinder until it is closed to 10 the other cylinder and is closed at all other times during the revolution of the valve.
3. In a gas engine, a pair of cylinders, a valve casing secured to the said cylinders and common to both of the same and having 15 an intake and an exhaust port communicating with each cylinder, and a tubular rotating valve having an intake chamber and an exhaust chamber therein, there being a single intake port in the walls of the valve inclos- 20 ing the intake chamber for supplying both said cylinders, a single exhaust port in the walls of the valve inclosing the exhaust chamber for exhausting both said cylinders, and a port in the walls of the valve inclos- 25 ing the intake chamber for the admission of an explosive mixture to the said intake chamber, which latter named port is open to a supply passage in said valve casing during the time the said intake port is 30 opened to both the said cylinders and closed at other times during the revolution of the valve.
4. In a gas engine, a pair of cylinders, a cylinder head and valve casing secured to 35 said cylinders and common to both of the same and having an intake passage to each cylinder and an exhaust passage from each cylinder, and a tubular rotating valve closed at one end and provided approximately 40 centrally with a transverse partition wall dividing the same into an intake chamber and an exhaust chamber, there being an intake port in the walls of the valve surrounding the intake chamber adapted to 45 register with the passages in the cylinder head and valve casing communicating with said cylinders, a single exhaust port in the
- walls of the valve surrounding the exhaust chamber therein adapted to register with the passages in the cylinder head and valve case which lead from the said cylinders, and a port adjacent the closed end of the valve for admitting an explosive mixture to the said intake chamber in the valve, which last aforesaid port is open to a supply passage 50 in said valve casing from the time the intake port is opened to one cylinder until the intake port is closed to the other cylinder and is closed during the entire remainder of the revolution of the valve. 55
5. In a gas engine, a pair of cylinders, a cylinder head and valve case secured to said cylinders and common to both of the same and having an intake passage to each cylinder and an exhaust passage from each cylinder, 60 a tubular rotating valve closed at one end and provided approximately centrally with a transverse partition wall dividing the same into an intake chamber and an exhaust chamber, there being an intake port in the walls of the valve surrounding the intake chamber adapted to register with the passages in the cylinder head and valve case which lead from the said cylinders, a single exhaust port in the walls of the valve surrounding the exhaust chamber 65 therein adapted to register with the passages in the cylinder head and valve case which lead from the said cylinders, an inlet nozzle associated with the cylinder head and valve case, a bearing forming part of said inlet nozzle, and a reduced end part extending from the closed end of the valve and passing through and being journaled in the said bearing, there being a port adjacent 70 the closed end of the said valve adapted to register with the passage in the inlet nozzle, which last aforesaid port is open to the inlet nozzle from the time the inlet port is opened to one cylinder until it is closed to the other 75 cylinder and closed at all other times during the revolution of the valve. 80
- Signed by me this 4th day of April, 1917.
SAMUEL LAWSON.
